CLAIM

The ornamental design for a prosthesis for a lower extremity, as shown and described.

DESCRIPTION

FIG. 1 is a top perspective view of a prosthesis for a lower extremity according to the present invention;

FIG. 2 is another top perspective view thereof;

FIG. 3 is right side view thereof;

FIG. 4 is front view thereof;

FIG. 5 is left side view thereof;

FIG. 6 is rear view thereof; and,

FIG. 7 is top view thereof.

The broken lines shown in the figures illustrate unclaimed portions of the prosthesis for a lower extremity.
